(74) Attorney, Agent, or Firm — Nath, Goldberg & Meyer; Jerald L. Meyer

(57) **CLAIM**

The ornamental design for the safety lock, as shown and described.

DESCRIPTION

FIG. 1 is a perspective view of an embodiment of our safety lock;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines depict portions of the article that form no part of the claimed design.
